Patented Feb. 27, 1917.

Fig. 2.

UNITED STATES PATENT OFFICE.

FRANK NORMAN, OF DES MOINES, IOWA, ASSIGNOR OF EIGHT THIRTY-SECONDS TO DOUGLAS J. LANDERS, SEVEN THIRTY-SECONDS TO WILLIAM A. MCATEE, FOUR THIRTY-SECONDS TO ALPHONSO B. LOVAN, ONE THIRTY-SECOND TO WILLIAM T. SHORES, AND TWO THIRTY-SECONDS TO GEORGE W. YOUNG, ALL OF SPRINGFIELD, MISSOURI, AND TWO THIRTY-SECONDS TO CLARENCE H. NICHOLS, OF NEW YORK, N. Y.

ACETYLENE-GAS MIXER.

1,217,634.

Specification of Letters Patent. Patented Feb. 27, 1917.

Application filed June 24, 1916. Serial No. 105,606.

To all whom it may concern:

Be it known that I, FRANK NORMAN, a citizen of the United States, residing at the city of Des Moines, county of Polk, and 5 State of Iowa, have invented a new and useful Acetylene-Gas Mixer, of which the following is a specification.

This invention relates to acetylene gas mixers.

10 The invention is primarily for use in an acetylene generating system for automobiles, in which the acetylene system displaces or is in addition to the gasoline supply and carbureting system, although it will be apparent from the following description that 15 the invention is capable of use equally as well in any acetylene generating system combined with an engine or motor; whether for the propulsion of a vehicle or other driven 20 mechanism. Therefore, it will be understood that in describing the invention, I do not restrict myself to any single use of it, or to its embodiment in any particular combination to exclusion of others, but it will be 25 understood that the invention is claimed in any use and embodiment to which it may be applied.

An object of the invention is to provide a 30 device for mixing the proper quantities of air and acetylene gas in an acetylene generating system, including a mixing chamber and a valve controlling the admission of the acetylene gas into the chamber from the generating or supply sources of the system, 35 in combination with an automatic valve controlling the admission of air into the mixing chamber as an incident to the withdrawal of the mixed air and gas from the mixing chamber by operation of the motor, and 40 means for varying the resistance of the valve to the pressure of the gas.

A further object is to provide an improved 45 device of the character mentioned, comprising a mixing chamber having passages adapted to admit the acetylene gas and also provided with passages for the admission of air, independently operating automatic valves for the gas and air passages respectively, which valves are controlled to regulate 50 the admission of air and gas in proper quantities and proportions by and as an in-

cident to the operation of the motor, and means for varying the resistance of said valves, equally or relatively, to maintain proper mixture under any circumstances and 55 conditions.

Further objects will appear from the following description, reference being made to the accompanying drawing illustrating a preferred embodiment of the invention, in 60 which—

Figure 1 is a side elevation of an acetylene gas mixer constructed in accordance with the present invention.

Fig. 2 is a longitudinal sectional view 65 thereof.

Fig. 3 is a sectional view on the line 3—3 of Fig. 2, illustrating the air passages and the valve device controlling them.

Fig. 4 is a sectional view on the line 4—4 70 of Fig. 2, illustrating the gas passages and the valve device controlling them.

The mixer illustrated includes a casing 1 which may be in the form of a cylinder as illustrated, or of any other preferred design. One end of the casing is interiorly threaded, as clearly illustrated in Fig. 2. An annular gas receiving chamber 2 is formed in the casing 1 by an element comprising an outer flange or wall 3 and an inner flange or wall 4 united by a reduced connecting portion 5 which is located axially within the casing 1. Thus the annular gas receiving chamber 2 is formed within the casing 1 between the walls 3 and 4 and 80 around the connecting portion 5. A pipe 6 communicating with the gas generating or supply source opens into the receiving chamber 2 so that said chamber receives a constant supply of gas when the device is in use 85 or operation. The walls 3 and 4 are formed with external threads which engage with the threads in the casing 1 and thereby retain the element forming the gas receiving chamber rigidly in proper connection with the 90 casing 1 in which it is mounted. The outer flange or wall 3 may be provided with recesses, illustrated at 7, with which any appropriate tool or appliance may be engaged for assembling or detaching the chamber 100 forming element. The inner wall 4 constitutes one end wall of a mixing chamber 8

into which the gas is admitted from the receiving chamber 2 through a series of passages 9 formed through the wall 4.

The surface of the end wall 4 of the mixing chamber is formed with a concave depression constituting a seat for an appropriately shaped puppet valve 10 which, when in closed position, closes the passages 9 and prevents the gas from entering the mixing chamber from the receiving chamber 2. The valve 10 is in connection with a valve stem 11 passing through an axial opening in the connecting portion 5 and the end walls 3 and 4. The outer portion of the valve stem 11 is encircled by a coiled spring 12 of the expansion type, the inner end of which bears against the outer wall 3, and the outer end of which has bearing against a plate or washer 13 which is adjustable upon the valve stem as required to vary the tension of the spring 12, in order to vary the resistance of the valve to the pressure of the gas. The adjusting device for the plate 13 comprises a nut 14 having threaded engagement with the valve stem so that by changing the position of the nut, the location of the abutment plate or washer 13 may be changed, thus varying the tension of the spring and the resistance of the valve to the pressure of the gas.

The pressure of the gas against the valve 10 through the passages 9 will open the valve in opposition to the power of the spring 12 and admit a continuing supply of the gas into the mixing chamber 8 to replace the gas which is drawn from the mixing chamber by operation of the motor or engine. The outer end of the valve rod 11 is covered by a removable cap 15 which screws into the threaded end of the casing 1 and coöperates with the end wall 3 to prevent escape of the gas from the receiving chamber and also from the mixing chamber.

The opposite end wall 16 of the mixing chamber may also be removable, as shown, in which case it has threaded engagement with the casing 1. A series of air passages 17 opens through the end wall for admitting air into the mixing chamber 8, where it forms an admixture with the gas. A concave depression is formed in the inner surface of the end wall 16 and constitutes a seat for the puppet valve 18 which, when in closed position, closes the air passages 17 as illustrated in Fig. 2. The valve 18 is in connection with a valve stem 19 which passes through and has bearing for axial movement in an appropriate opening in the end wall and which is encircled by a coil spring 20 of the expansion type. One end of the spring 20 bears against the wall 16 and the opposite end bears against an adjustable plate or washer 21 mounted on the valve stem and capable of adjustment thereon to vary the power or tension of the spring 20

as required to regulate the operation of the valve. The means for adjusting the plate or washer 21 comprises a nut 22 threaded upon the end of the valve stem and capable of adjustment thereon to change the position of the plate or washer 21 as required to vary the tension of the spring, in order to vary the resistance of the valve to the pressure of the air.

The admixture from the mixing chamber 8 is conducted to the manifold of an engine or motor through a passage 23. The supply of gas into the receiving chamber, and consequently to the mixing chamber and to the engine or motor, is controlled by a throttle valve 24 in the pipe 6. The throttle valve is of the usual and well known automatic closing type the details of which are no part of the present invention and require no detailed illustration and may be opened by the usual manipulative throttle connections 25.

What I claim and desire to secure by Letters Patent of the United States, is:—

1. An acetylene gas mixer, comprising a casing, an inner wall secured within the casing intermediate of the ends thereof, an outer wall secured within the casing intermediate of the ends thereof, a gas receiving chamber within the casing whose walls are the casing and said inner and outer walls, an end wall secured to the casing, a mixing chamber within the casing between the end wall and the inner wall, passages from the receiving chamber through the inner wall into the mixing chamber, a puppet valve controlling said passages, a stem in connection with said valve extending through said inner and outer walls, a spring normally retaining said puppet valve in position to close said passages and arranged to yield under the pressure of the gas against said valve to enable the gas to enter the mixing chamber, passages through said end wall for admitting air into said mixing chamber, a puppet valve controlling the air passages, and a spring normally retaining the last-named puppet valve in position to close the air passages and arranged to yield under pressure of the air against said valve to enable the air to enter the mixing chamber.

2. An acetylene gas mixer, comprising a casing, two walls removably mounted transversely within said casing and having their edges in connection therewith, an axial connection between said walls, a gas receiving chamber in said casing between said walls and around said connection, a mixing chamber in said casing, passages from said receiving chamber through one of said walls to said mixing chamber, a puppet valve controlling said passages, a stem in connection with said valve extending through both of said walls, a spring encircling said valve stem outside said outer wall normally retaining said puppet valve in position to

close said passages and arranged to yield under the pressure of the gas against said valve to enable the gas to enter the mixing chamber, an adjustable abutment for said 5 spring on said valve stem for varying the tension of said spring and thereby the resistance of said valve against the pressure of the gas, passages for admitting air into said mixing chamber, a puppet valve controlling 10 said air passages, and a spring normally retaining said last-named puppet valve in position to close said air passages and arranged to yield under the pressure of the air against said valve to enable the air to enter the 15 mixing chamber.

3. An acetylene gas mixer, comprising a casing, a gas receiving chamber in said casing, an outer transverse wall removably mounted in said casing, an inner transverse 20 wall within said casing spaced from and integrally connected to said outer wall, an end wall in connection with the casing, a mixing chamber in said casing formed by said inner and end walls and the wall of the casing, 25 passages from said receiving chamber through said inner wall to said mixing chamber, a puppet valve controlling said passages, a valve stem in connection with said valve extending through said walls, a 30 spring encircling said stem bearing against said outer wall and normally retaining said puppet valve in position to close said passages and arranged to yield under the pressure of the gas against said valve to enable 35 the gas to enter the mixing chamber, means for varying the tension of said spring and thereby the resistance of said valve against the pressure of the gas, a puppet valve controlling said air passages, a spring normally 40 retaining said last-named puppet valve in position to close said air passages and arranged to yield under the pressure of the air against said valve to enable the air to enter the mixing chamber, and means for varying 45 the tension of said last-named spring and thereby the resistance of the second-named puppet valve against the pressure of the air.

4. An acetylene gas mixer, comprising a 50 casing; an element, removably mounted in said casing, comprising an inner wall, an outer wall and an axial connection uniting said walls; a gas receiving chamber formed between said inner and outer walls within the casing around said connection; a passage 55 for admitting gas into said chamber; a mixing chamber within said casing; a series of passages from said receiving chamber into said mixing chamber; a valve controlling said series of passages; a valve stem in connection with said valve extending through said inner and outer walls and through said 60 connection; a spring encircling said valve stem and arranged to hold said valve in position to close said series of passages and to yield to the pressure of the gas; a device for admitting gas into said chamber; a puppet valve 65 controlling said air passages; and a spring for holding said puppet valve in closed adjustment and arranged to yield to the pressure of the air to admit air into the mixing chamber as an incident to the withdrawal of the mixture from said chamber.

varying the tension of said spring to vary the resistance of the valve against the pressure of the gas, air inlet passages opening into said mixing chamber, and means for controlling the passage of air through said 70 passages.

5. An acetylene gas mixer, comprising a casing; an element, removably mounted in said casing, comprising an inner wall, an outer wall and an axial connection uniting 75 said walls; a gas receiving chamber formed between said inner and outer walls within the casing around said connection; a passage for admitting gas into said chamber; a mixing chamber within said casing; a series of 80 passages from said receiving chamber into said mixing chamber; a valve controlling said series of passages; a valve stem in connection with said valve extending through said inner and outer walls and through said connection; a spring encircling said valve stem and arranged to hold said valve in position to close said series of passages and to yield to the pressure of the gas; a device for varying the tension of said spring to 85 vary the resistance of the valve against the pressure of the gas; and passages for admitting air into said mixing chamber.

6. An acetylene gas mixer, comprising a casing; an element, removably mounted in 90 said casing, comprising an inner wall, an outer wall and an axial connection uniting said walls; a gas receiving chamber formed between said inner and outer walls within the casing around said connection; a passage 95 for admitting gas into said chamber; a mixing chamber within said casing; a series of passages from said receiving chamber into said mixing chamber; a valve controlling said series of passages; a valve stem in connection with said valve extending through said inner and outer walls and through said connection; a spring encircling said valve stem and arranged to hold said valve in position to close said series of passages and to yield to the pressure of the gas; a device for varying the tension of said spring to 100 vary the resistance of the valve against the pressure of the gas; and passages for admitting air into said mixing chamber; a puppet valve 105 controlling said air passages; and a spring for holding said puppet valve in closed adjustment and arranged to yield to the pressure of the air to admit air into the mixing chamber as an incident to the withdrawal of the mixture from said chamber.

7. An acetylene gas mixer, comprising a 110 casing; an element, removably mounted in said casing, comprising an inner transverse wall, an outer transverse wall and a connection uniting said walls; a gas receiving chamber formed by said walls and the wall of the casing; a passage opening into said casing between said inner and outer walls for admitting gas into said chamber; a mix- 115 120 125 130

- ing chamber within said casing; a recess constituting a valve seat in the side of the inner wall in said mixing chamber; passages from said receiving chamber into said 5 recessed valve seat; a valve movable into and out of said valve seat for controlling said passages; a valve stem in connection with said valve extending through said walls and through said connection; a spring 10 encircling said valve stem and arranged to hold said valve in said valve seat to close said passages and to yield to the pressure of the gas; a device for varying the tension of said spring to vary the resistance of the 15 valve against the pressure of the gas; a cap inclosing said spring and device and engaging said casing; passages for admitting air into said mixing chamber; a puppet valve controlling said air passages; a spring 20 for holding said puppet valve in closed adjustment and arranged to yield to the pressure of the air to admit air into the mixing chamber as an incident to the withdrawal of the mixture from said chamber; and means 25 for varying the tension of said last-named spring to vary the resistance of the valve against the pressure of the air.
8. An acetylene gas mixer, comprising a casing; an element incased within said casing comprising inner and outer walls having their edges in engagement with the casing and forming a closed receiving chamber within the casing between said walls; a connection between said walls; a mixing chamber within said casing; a series of passages through the inner wall of said element for admitting gas from the receiving chamber into the mixing chamber; a puppet valve for opening and closing said series of passages; 30 a spring arranged to hold said valve in position to close said series of passages and to yield to the pressure of the gas within the receiving chamber as an incident to the withdrawal of the gas from the mixing chamber; 35 passages for admitting air into the mixing chamber; a valve controlling said air passages and arranged to yield to the pressure 40 of the air to admit air into the mixing chamber; a spring for holding said last-named valve in position to close said air passages; and means for varying the tension of said spring to vary the resistance of said valve against the pressure of the air, whereby the relative quantities of air and gas entering said mixing chamber may be varied. 45
9. An acetylene gas mixer, comprising a casing; an element incased within said casing, comprising inner and outer walls having their edges engaging the wall of the casing and forming a closed gas receiving chamber between them; an axial connection between said walls; a mixing chamber within said casing around said connection; passages from said receiving chamber into said mixing chamber; a valve for controlling 50 said passages; a spring arranged to hold said valve in position to close said passages against the pressure of the gas and to yield to the pressure of the gas against said valve; a passage for admitting gas into said receiving chamber; passages for admitting air into said mixing chamber; a valve controlling 55 said air passages; a valve stem in connection with said last-named valve; a spring encircling said valve stem and arranged to hold said valve in position to close said air 60 passages and to yield to the pressure of the air to enable air to enter said mixing chamber as an incident to the withdrawal of gas and air from said mixing chamber; a passage for withdrawing the mixed air and gas from said mixing chamber; and means for varying relatively the tension of said 65 springs whereby relative quantities of air and gas entering said mixing chamber may be optionally varied.
- In witness whereof, I have signed this specification in the presence of two subscribing witnesses.

FRANK NORMAN.
